United States Patent Office

Des. 197,614
Patented Mar. 3, 1964

197,614

DESK

David C. Still, 1107 California Ave., Santa Monica, Calif.

Filed Aug. 1, 1963, Ser. No. 76,074

Term of patent 14 years

(Cl. D33—7)

Fig. 1.

3—

Fig. 2.

3—

Fig. 3.

FIG. 4.

FIG. 5.

FIG. 6.

I claim:

The ornamental design for a desk, substantially as shown.
